TABLE LEG LENGTH EQUALIZER

Charles Edward Barker, San Francisco, Calif.

Application August 26, 1935, Serial No. 38,003

6 Claims. (Cl. 45—139)

My invention relates to improvements in table leg length equalizers, and it consists of the combinations, constructions and arrangements hereinafter described and claimed.

5 In tables such as those used in restaurants it is practically impossible to cause all of the legs of the table to uniformly rest on the floor. One of the legs will be shorter than the others, or the floor will be uneven, and thus prevent all of the 10 legs from contacting with the floor. If only three of the four legs engage with the floor the table will rock very easily.

It is the object of the present invention to provide a table leg length equalizer which will automatically accommodate itself to the supporting surface, and thus prevent the table from rocking. In a table provided with four legs only two of the devices need be used, and these are placed in the bottoms of two adjacent legs.

20 The device is extremely simple in construction, and is durable and efficient for the purpose intended. I provide novel means for varying the tension of the spring housed in the device, and in this simple way the device can be accommodated to tables of varying weights.

Other objects and advantages will appear in the following specification, and the novel features of the device will be particularly pointed out in the appended claims.

30 My invention is illustrated in the accompanying drawing forming a part of this application, in which

Figure 1 is a vertical section through the device showing it operatively applied in the bottom of 35 a table leg or the like;

Figure 2 is a section along the line 2—2 of Figure 1; and

Figure 3 is a side elevation of the two parts of the casing shown separated from each other.

40 In carrying out my invention I provide an outer shell or casing 1 that has a closed top 2. An inner shell or casing 3 has a closed bottom 4, and the inner shell is slidably and rotatably received in the outer shell. The inner shell 3 has 45 an annular groove 5 in its outer surface, and this groove is relatively wide. The outer shell carries adjusting screws 6 and these screws are threaded into the annular groove 5 after the two shells have been assembled. The screws permit 50 a rotation and a longitudinal movement of the inner shell 3 with respect to the outer shell 1. Figure 3 shows a side elevation of the outer shell 1, and is taken at right angles to the views shown in Figure 1. The purpose of this is to more 55

clearly illustrate the position of one of the set screws 6.

The inner shell 3 is urged away from the outer shell 1 by means of a spring 7. This spring has its upper end inserted through an opening 8 in the top 2 of the outer shell, and this end is upset as at 9 for anchoring the spring against rotation. The inner shell 3 has a spirally grooved portion 10 for receiving the lower loops of the spring 7. A kerf 11 is provided at the bottom 4 and a screw 10 driver may be placed in this kerf for rotating the inner shell with respect to the outer one. A rotation of the inner shell will cause a greater or a fewer number of loops of the spring 7 to be received in the spiral groove 10. The result is a 15 change in the tension of the spring 7. In this simple way the spring may be adjusted to accommodate various weights of tables.

A bore or recess 12 is provided in the bottom of a table leg 13, and the outer shell is placed in this bore so that its bottom edge 14 will lie flush with the bottom edge 15 of the table leg. The shell 1 may be secured to the table leg in any desired manner such as by forming a friction fit with the wall of the bore. The inner shell 3 is 25 now rotated, and will tension the spring 7 to the desired point. The device is now ready for use.

The table in resting on the supporting surface 16 will have two of its adjacent legs 13 provided with the device. The inner shells 3 of these two devices will be urged outwardly by the springs 7 with the result that the bottoms 4 of the inner shells will engage with the floor and will support the table in such a manner as to prevent its 30 rocking.

While I have shown only the preferred form of my invention, it should be understood that various changes or modifications may be made within the scope of the appended claims without departing from the spirit of the invention.

I claim:

1. A table leg length equalizer comprising an outer shell designed to be placed in the bottom of a table leg, an inner shell slidably and rotatably mounted in the outer shell, means for securing 45 the two shells together while permitting rotational movement between the two and a longitudinal movement within predetermined limits, and a spring bearing against the ends of the two shells for holding the inner shell in contact with 50 a supporting surface.

2. A table leg length equalizer comprising an outer shell designed to be placed in the bottom of a table leg, an inner shell slidably and rotatably mounted in the outer shell, means for securing 55

- the two shells together while permitting rotational movement between the two and a longitudinal movement within predetermined limits, and a spring bearing against the ends of the two shells for holding the inner shell in contact with a supporting surface, and means carried by the inner shell for varying the compression of the spring by rotating the inner shell within the outer shell.
5. A table leg length equalizer comprising an outer shell designed to be placed in the bottom of a table leg, an inner shell slidably and rotatably mounted in the outer shell, means for securing the two shells together while permitting rotational movement between the two and a longitudinal movement within predetermined limits, and a spring bearing against the ends of the two shells for holding the inner shell in contact with a supporting surface, the inner shell being provided with grooves for receiving a greater or less portion of the spring when the inner shell is rotated in one direction or the other, whereby the compression of the spring may be varied.
10. 3. A table leg length equalizer comprising an outer shell placed in the bottom of a table leg, an inner shell slidably mounted in the outer shell and being provided with a relatively wide annular groove in its outer surface, screws carried by the outer shell and being slidably received in the
15. 4. A table leg length equalizer comprising an outer shell placed in the bottom of a table leg, an inner shell slidably mounted in the outer shell and being provided with a relatively wide annular groove in its outer surface, screws carried by the outer shell and being slidably received in the
20. 5. A table leg length equalizer comprising an outer shell placed in the bottom of a table leg, an inner shell slidably mounted in the outer shell and being provided with a relatively wide annular groove in its outer surface, screws carried by the outer shell and being slidably received in the
25. 6. The combination with an article of furniture supported by legs, of leg equalizers applied to at least two of the legs that are disposed adjacent to one another, each equalizer including an active spring actuated member yieldingly held in contact with the supporting surface at all times, whereby the effective lengths of the legs to which the equalizers are attached will at all times extend to the supporting surface and will prevent the rocking of the furniture on the legs, and means for varying the force exerted by the spring to accommodate the equalizer to the weight of the device to which it is attached.

groove, a spring anchored to the outer shell, the inner shell having grooves for receiving the lower loops of the spring.

5. A table leg length equalizer comprising an outer shell placed in the bottom of a table leg, an inner shell slidably mounted in the outer shell and being provided with a relatively wide annular groove in its outer surface, screws carried by the outer shell and being slidably received in the groove, a spring anchored to the outer shell, the inner shell having grooves for receiving the lower loops of the spring, the compression of the spring being varied by rotating the inner shell for causing the desired number of loops of the spring to be received in the grooves.

6. The combination with an article of furniture supported by legs, of leg equalizers applied to at least two of the legs that are disposed adjacent to one another, each equalizer including an active spring actuated member yieldingly held in contact with the supporting surface at all times, whereby the effective lengths of the legs to which the equalizers are attached will at all times extend to the supporting surface and will prevent the rocking of the furniture on the legs, and means for varying the force exerted by the spring to accommodate the equalizer to the weight of the device to which it is attached.

CHARLES EDWARD BARKER.
